UNITED STATES PATENT OFFICE.

DON A. CLARK, OF CLEVELAND, OHIO, ASSIGNOR TO THE DUSTON AND CLARK ENGINEERING COMPANY, OF CLEVELAND, OHIO, A CORPORATION OF OHIO.

ROLLING MILL.

Application filed August 28, 1926. Serial No. 132,256.

My invention relates to rolling mills or the like, and particularly to means for eliminating irregularities in the material being rolled, and the principal object of my invention is to provide a mill embodying such means. In the drawings accompanying this specification and forming a part of this application I have shown, for purposes of illustration, one form which my invention may assume. In these drawings:

Figure 1 is a general side elevation of the embodiment of my invention herein shown,

Figure 2 is a central vertical section through the means for operating the mill rolls from the slow speed drive shaft, while

Figure 3 is a central vertical section through the means for operating the slow speed drive shaft from the high speed drive shaft connected to the driving motor.

The embodiment of my invention herein shown comprises generally a rolling mill, and driving means for operating the mill tending to operate the mill rolls at somewhat different speeds, but permitting the material being rolled forcing said rolls to operate at substantially the same speed.

The embodiment of my invention herein shown comprises a rolling mill 11, a rolling mill operating head 12, a speed reduction mechanism 13, and an operating motor 14, all suitably connected.

The rolling mill 11 comprises a pair of uprights 15 mounted upon a bed plate 16 and braced by suitable cross connections 17, and a pair of rolls 18 and 19 cooperating to roll material therebetween and mounted upon shafts 20 and 21 rotatably supported in the uprights 15 and provided on their ends adjacent the rolling mill drive shaft 12 with reduced polygonal extensions 22 and 23 respectively.

The rolling mill operating head 12 comprises a pair of uprights 24 also mounted upon the bed plate 16, a lower drive shaft 25 rotatably supported in the uprights 24 and provided with a reduced polygonal extension 26 arranged to be non-rotatably received within a cooperatively formed polygonal recess 27 in the adjacent end of a wobbler 28 provided on its other end with a polygonal recess 29 cooperatively formed to non-rotatably receive the polygonal projection 23 on the shaft 21 of the mill roll 19, a gear 30 splined to the lower drive shaft 25, an annular shaft 31 rotatably

mounted in the uprights 24 vertically above the lower drive shaft 25, a gear 32 intermeshing with the gear 30 on the lower drive shaft 25 and splined to the annular shaft 31 and formed of less diameter than the gear 30 to cause the annular shaft 31 to rotate at a somewhat greater speed than the lower drive shaft 25, an upper drive shaft 33 rotatably mounted within the annular shaft 31 and provided with a reduced polygonal extension 34 arranged to be non-rotatably received within a cooperatively formed polygonal aperture 35 in the adjacent end of a wobbler 36 provided at its other end with a polygonal recess 37 cooperatively formed to non-rotatably receive the polygonal extension 22 projecting from the shaft 30 of the mill roll 18, and transmitting means 38 operatively connecting the annular shaft 31 to the upper drive shaft 33 tending to rotate the upper drive shaft 33 synchronously with the annular shaft 31, and therefore at a higher speed than the lower drive shaft 25, but permitting the slippage between the annular shaft 31 and the upper drive shaft 33 necessary to permit the material being rolled forcing the rolls 18 and 19 to operate at substantially the same speed in spite of the operation of the annular shaft 31 at a higher speed than the lower drive shaft 25.

The connecting means 38 herein shown comprises a spider 39 carrying a plurality of stud shafts 40 each rotatably supporting a planet gear 41, an external gear 42 meshing with the various planet gears 41 and carried by a cylindrical member 43 secured by means of spokes 44 to a hub 45 splined to the upper drive shaft 33, a sun gear 46 also meshing with the various planet gears 41 and freely rotatable upon the upper drive shaft 33, a brake wheel 47 splined to the sun gear 46 and disposed within the cylindrical member 43 carrying the external gear 42, and a plurality of brake shoes 48 adjustably mounted upon the cylindrical member 43 in contact with the brake drum 47 carried by the sun gear 46.

The drive for the rolling mill mechanism is herein shown as comprising a speed reduced mechanism 13 interposed between and connecting the high speed shaft 49 of the electric motor 14 and the low speed lower drive shaft 25 of the rolling mill mechanism.

This reduction mechanism 13 comprises a

housing 50 fixedly mounted upon a suitable base 51 and containing on its interior an external gear 52 meshing with a plurality of planet gears 53 rotatably mounted upon stud shafts 54 carried by a planet carrier 55 rotatably supported within annular bosses 56 projecting from the two sides of the casing 50, a low speed shaft 57 splined to and supported by the planet carrier 55 and provided with a polygonal extension 58 non-rotatably inter-engaging with a cooperatively formed polygonal recess in the adjacent end of the lower drive shaft 25, and a high speed shaft 59 rotatably mounted within the adjacent portion of the planet carrier 55, carrying a sun gear 60 meshing with the various planet gears, and connected to the electric motor 14 by means of a polygonal projection 61 extending from the driving shaft 59 and non-rotatably inter-engaging with a correspondingly shaped polygonal recess in the adjacent end of the motor shaft 49.

From the above description it will be obvious to those skilled in the art that operation of the motor 14 rotates the high speed shaft 59 and sun gear 60 to cause the planet gears 53 to rotate both about their individual axes 54 and also, because of their engagement with the stationary external gear 52, bodily about the axis of the high speed shaft 59, and that this latter motion causes a rotation of the planet carrier 55 which is transmitted through the low speed shaft 57 and connection 58 to the lower driving shaft 25.

From the above description it will also be obvious that operation of the lower drive shaft 25 will act through the lower wobbler 28 to directly rotate the lower mill shaft 21 and the lower roll 19, that operation of the upper drive shaft 33 will act through the upper wobbler 36 to rotate the upper mill shaft 20 and the upper mill roll 18, and that rotation of the lower drive shaft 25 will act through the gears 30 and 32 to rotate the annular shaft 31 at a speed somewhat greater than the speed of rotation of the lower drive shaft 25.

From the above description of the power transmitting device 38 it will be obvious to those skilled in the art that the external gear 48 and the planet gears 41 and the sun gear 46 comprise a differential transmission, that bodily rotation of the planet gears 41 will rotate the sun gear 46 and external gear 42 differentially, that the interaction of the brake shoes 48 carried by the cylindrical member 43 and the brake drum 47 carried by the sun gear 46 will tend to cause the sun gear 46 and the external gear 42 to rotate synchronously with each other and therefore, by eliminating the differential rotation of the planet gears 41, to rotate synchronously with the bodily rotation of the planet gears 41, that by this action the power transmission mechanism 38 tends to rotate the upper

drive shaft 33 synchronously with the annular shaft 31, that the connections between the brake shoes 38 on the cylindrical member 43 and the brake drum 37 on the sun gear 46 will permit differential rotation of the sun gear 46 and the external gear 42 to permit the external gear 42 to rotate at a lower speed than the speed of bodily rotation of the planet gears 41, the speed of rotation of the annular shaft 31, and that this slippage between the brake shoes 48 and brake drum 47 therefore permits the upper drive shaft 33 to rotate at a speed lower than the speed of rotation of the annular shaft 31.

It will therefore be obvious to those skilled in the art that operation of the lower drive shaft 25 will act through the annular shaft 31 and power transmitting mechanism 38 to tend to rotate the upper drive shaft 33 and the upper mill roll 18 at a greater speed than the speed of rotation of the lower mill roll 19, but that the power transmitting mechanism 38 is effective to permit the material being rolled to force the mill rolls 18 and 19 to rotate at substantially the same speed even against the tendency of the upper mill roll 18 to rotate at the higher speed.

Under these circumstances it will be obvious to those skilled in the art that the driving mechanism is constantly tending to drive the upper roll 18 at a higher speed than the speed at which the driving mechanism operates the lower roll 19, and that this tendency persists even when the material being rolled forces the two rolls to operate at substantially the same speed.

I find the construction herein shown and described rolls material free from many of the imperfections heretofore usual, and particularly free from the waves usual in rolled material, and I ascribe this to the maintenance of the rolls and connections constantly under tension, and to the consequent elimination of the chattering universally present in rolling mills.

At the same time I, of course do not limit my invention to operation under this or any other particular theory.

From the above description it will now be obvious to those skilled in the art that I have produced new and improved mechanism satisfying at least the principal object of my invention.

At the same time it will also be obvious to those skilled in the art that the particular embodiment of my invention herein shown and described may be variously changed and modified without departing from the spirit of my invention or sacrificing the advantages thereof, and it will therefore be understood that the disclosure herein is illustrative only, and that my invention is not limited thereto.

I claim:

1. In a rolling mill or the like, a pair of

13. In a rolling mill or the like, a pair of rolls cooperating to roll material therebetween, and driving means for said rolls connected to said rolls constructed to operate 5 said rolls at somewhat different peripheral speeds one faster than the other, but comprising an impositive connection interposed in the drive of said one roll permitting the material being rolled forcing said one roll 10 to operate only at substantially the speed of said other roll, each roll operating to feed said material.
14. In a rolling mill or the like, a pair of rolls cooperating to roll material therebetween, and driving means for said rolls connected to said rolls constructed to operate said rolls at somewhat different peripheral speeds one faster than the other, but comprising a frictional connection interposed 15 in the drive of said one roll permitting the material being rolled forcing said one roll to operate only at substantially the speed of said other roll, each roll operating to feed said material.
15. In a rolling mill or the like, a pair of rolls cooperating to roll material therebetween, and a single driving means for said rolls connected to said rolls constructed to operate said rolls at somewhat different peripheral speeds one faster than the other, but comprising an impositive connection interposed 20 in the drive of said one roll permitting the material being rolled forcing said one roll to operate only at substantially the speed of said other roll, each roll operating to feed said material.
16. In a rolling mill or the like, a pair of rolls cooperating to roll material therebetween, and a single driving means for said rolls connected to said rolls constructed to 25 operate said rolls at somewhat different peripheral speeds one faster than the other, but comprising a frictional connection interposed in the drive of said one roll permitting the material being rolled forcing said one roll to operate only at substantially the speed of said other roll, each roll operating to feed said material.
17. Transmission mechanism comprising a differential transmission having a driven element and a driving element and a third element connected differentially to said driven element and said driving element, and connecting means adapted to connect said third element to another of said elements by an impositive frictional connection 30 between two members connected to rotate in the same direction upon operation of said mechanism.
18. Transmission mechanism comprising a differential transmission having a driven element and a driving element and a third element connected differentially to said driven element and said driving element, and connecting means adapted to connect said third element to said driven element by an impositive frictional connection between two members connected to rotate in the same direction upon operation of said mechanism.

In testimony whereof I hereunto affix my 70
signature.

DON A. CLARK.
